UNITED STATES PATENT OFFICE.

THOMAS WILLIAM HELLIWELL, OF BRIGHOUSE, COUNTY OF YORK,
ENGLAND.

GLAZED ROOF.

SPECIFICATION forming part of Letters Patent No. 355,079, dated December 28, 1886.

Application filed June 23, 1886. Serial No. 206,038. (No model.) Patented in England July 8, 1884, No. 9,886, and May 8, 1885, No. 5,684.

To all whom it may concern:

Be it known that I, THOMAS WILLIAM HELLIWELL, a subject of the Queen of Great Britain, residing in Brighouse, county of York, England, have invented certain new and useful Improvements in Glazed Roofs, of which the following is a specification.

This invention is the subject of patents in Great Britain, dated July 8, 1884, No. 9,886, (which covers the construction shown in Figs. 1 to 7 of the accompanying drawings,) and May 8, 1885, No. 5,684, (which covers the construction shown in Figs. 9 and 10 thereof.)

This invention has reference chiefly to glazed roofs, although it applies in part to metal roofs or roofs of other materials, as well as to sides of buildings or other structures.

In the accompanying drawings, Figure 1 is a perspective view of a fragment of a glass roof constructed according to my invention, showing the glazing-bar or rafter and the joint between this bar and the opposite sheets of glass in transverse section. Fig. 2 is a cross-section of the sealing-strip before being applied to the joint, and Fig. 3 is a cross-section thereof after being applied. The remaining figures illustrate modifications. Figs. 4, 5, 6, and 7 are perspective views on a smaller scale than Fig. 1, showing different constructions of glazed roofs. Fig. 8 is a cross-section of a modified construction of the sealing-strip. Fig. 9 is a perspective view of another modified construction of glazed roof, and Fig. 10 is a view of the sealing-strip used therewith.

In Fig. 1, let A designate one of the inclined glazing-bars of the roof, and B B the sheets of glass. The bar A is made in two pieces, or of two bars joined together side by side by screws d at intervals, or by other suitable means. The bar or rafter A is formed on its opposite sides with ledges a a, on which rest the edges of the glass sheets. In these ledges are formed grooves or gutters b b, which carry away any leakage through the joint. On the sides of the bar A, beneath the ledges a a, are channels or gutters c c, which carry away any moisture that may run over from the gutters b b, and any condensation-water that finds its way to the edges of the glass. The bar A projects

above the ledges a a and above the glass, and 50 along the middle of its projecting portion, lettered C, is cut a deep, narrow groove, e, which is enlarged at its bottom.

D is a sealing-strip, of lead, zinc, or other suitable metal or material, of Y shape in cross-section. In this construction it is made from a strip or ribbon of metal by bending the latter along its middle, bringing the side portions together face to face, and turning the edge portions away from each other, as shown in 55 Fig. 2. The middle portion is not creased flat, but is bent with a gentle curve, (as though bent around a wire,) thus forming a bead, or head, or enlargement, f, at the bottom of the Y. This Y-shaped strip D is inserted into the groove 60 e, its head f filling the enlargement at the bottom of the groove, its body g (Fig. 2) filling the groove up to the surface of the glazing-bar, and its wings h h (Fig. 2) projecting above the bar. When the sheets of glass have been 65 laid in place, these wings h h are turned down over the projecting portion C of the glazing-bar until their edges bear upon the glass and hold it down in place, as shown in Fig. 1. Fig. 3 shows the shape which the strip D then 70 assumes.

The Y-shaped strip D is made of soft metal, in order that when thus bent down it will remain in place. The lifting of the sheets of glass by pressure from beneath is prevented 75 by the head f on the strip D, which is too large to pull out of the groove e.

In Figure 1 is shown an additional feature of my invention. Before the wings h h are bent down there is inserted along each edge 80 of the glass, and against the projecting portion C of the glazing-bar, a piece of felt, i, or other soft and yielding or absorbent material, which is bent into L shape, and over this is placed an angle-strip, k, of sheet metal. 85 Then the wings h h are bent down over the angle-strips k k, thus holding all securely in place and making a water-tight joint. The outer edges of the angle-strips k k are turned down into contact with the glass, thereby 90 closing and concealing the felt i and preventing the escape or displacement of the latter. The angle-strips k k may be fastened to the

projecting-portion C of the bar by screws or nails at intervals, if desired, thereby adding to the strength of the joint.

When the roof is made with overlapping sheets of glass, as shown, some construction must be provided for preventing the slipping down of the sheets of glass. To this end I make the angle-strips k k only as long as the exposed portions of the sheets of glass, and I turn up their upper ends, as shown at l in Fig. 1, to form a stop against which the lower edge of the next sheet of glass above may abut. This effectually prevents the slipping down of the glass, since the strips k, by being fastened to the portion C of the glazing-bar, cannot be displaced. Thus to each joint as many strips k are used as there are sheets of glass; but by preference only one strip D is used, this being continuous from the ridge to the eaves, or from the top to the bottom of the skylight.

Underneath the glazing-bar is fastened a metal strip, E, having grooves along its opposite edges forming gutters m m. These are supplementary to the gutters b and c, and the metal strip imparts a desirable finish to the under side of the glazing-bar.

I will now proceed to describe some modifications of my invention applicable to glazed roofs.

Fig. 4 shows a construction wherein the glazing-bar A is made of only one piece, instead of two pieces fastened together. The metal strip E is omitted. The bar has the central projection, C, groove e, ledge a, and gutters b and c, as already described. The Y-shaped strip D is made in the same way, but as the bar A is in one piece this strip must be inserted in the groove e by letting it down from the top, and consequently its head f, Fig. 2, is unable to prevent the pulling out of the strip. Hence, in order to hold the strip securely down in the groove nails or screws n n are passed through the portion C and the body g of the strip D. After the sheets of glass B B have been laid strips of wood k k are laid upon them against the projection C, with their upper ends against the edges of the sheets of glass above, to prevent their slipping down. Putty or other plastic material may be used in place of or under the strips of wood. Finally, the wings h h, Fig. 2, of the strip D are turned down over the wood or putty k k, with their edges on the glass, thus concealing the wood or putty. This view shows two strips, D D, the upper one being lapped over the under one.

Fig. 5 shows a glazing-bar made in two pieces. The strip D is made somewhat wider, and its wings h h are turned down over the sides of the projection C, and its edges extend onto the surface of the glass for a short distance.

Fig. 6 shows a glazing-bar, A, of sheet metal, formed around a wooden or metal core or rafter, A'. The metal is bent to form the ledges a a and gutters b and c, and the wooden core has the groove e formed in it, which may be entered by the sheet metal forming the glazing-

bar or not, as preferred. If the glazing-bar is made in two parts, they will be fastened to the wooden core by screws d d. The metal strip D is inserted and turned down in the same manner as already explained.

Fig. 7 shows a modified construction wherein the glazing-bar is made of sheet metal wrapped around a metal core. The core A' is a bar, of 75 rolled iron or cast-iron or other metal, with a flange at its bottom, around which is wrapped the sheet metal, which is formed into a ledge, a, and gutter, b, and the two edges of which project upward to form the projection C and 80 stand close together, the narrow space between them forming the groove or opening e to receive the body g of the strip D. Screws, nails, rivets, or small bolts and nuts are passed through the metal plates to hold the strip D in 85 place. When the glass is set, the wings h h are turned down upon it, as shown.

In all its various forms or modifications my invention has the advantage, as applied to glass roofs, of making a neat and tight joint with but 90 little labor and by a simple construction, involving but few parts. The employment of the strips D of ductile metal makes the replacing of broken panes of glass to be very readily effected by merely turning up the wings, removing the broken glass, inserting a new pane, and turning the wings down to their place again.

It is not essential that the sealing-strip D be made of a strip of sheet metal doubled upon itself, as described, although this is preferable. 100 Fig 8 shows the sealing-strip made with its head f and body portion g solid or of one thickness. Such a strip without the head f is not novel with me.

Fig. 9 shows a glazed roof embodying a portion of my invention. The glazing-bar A has no groove e, but instead this groove or opening is substantially formed in the sealing-strip D, (shown in Fig. 10.) The body portion g of this strip is divided into two portions or flanges, 110 g' g', with a space or opening, e', between them wide enough to receive the projection C. Nails or rivets are put through, as at n, to hold the sealing-strip in place. When the glass has been laid in place, the wings h h of the sealing-strip are turned down upon it, as clearly shown.

My invention is not wholly confined to glazed roofs, but is in part applicable to certain kinds of metal roofing, such as roofs of sheet-lead, zinc, copper, tin, or other suitable roofing material. The metal sheets or plates are to be laid in place of the glass plates shown, it being preferable to turn up their lateral edges against the bars A, as is customary in other metal roofs heretofore made. A roof-sheathing 125 may be supplied to support the metal plates if found desirable.

By the novel constructions of roofing provided by my invention I avoid the use of bolts, screws, or nails, which are accessible to 130 the weather or to moisture, and make a joint which presents no external fastenings, and no holes or seams through which leakage may occur. The joint is readily sealed, and may be

as readily lifted for repairs to the roof-plates and again sealed.

I claim as my invention--

1. A sealing-strip, D, for sealing the joints of roofs, made of soft or ductile metal, and consisting of a head or flange, f, a body, g, and two wings, h h, substantially as set forth.
2. A sealing-strip, D, for sealing the joints of roofs, made of a strip of soft or ductile metal, bent upon itself to form a head or flange, f, at its middle, a body portion, g, of two thicknesses, and two wings, h h, of one thickness, adapted to be bent away from each other and turned down, substantially as set forth.
3. In a roof, the combination, with the roof-plates laid in courses, of a bar, A, between the courses, projecting above the edges of the plates, made in two pieces joined together, and having a groove, e, in its top, extending into the joint between said pieces, and enlarged at its bottom; and a sealing-strip, D, having a head or flange, f, fitting the enlargement in said groove, whereby the drawing out of the strip from the groove is prevented, substantially as set forth.
4. In a glazed roof, the combination, with the sheets of glass, of a glazing-bar, A, having ledges a, for supporting the edges of the glass, and a projection, C, extending up above the glass, and a sealing-strip, D, fixed to said projection, and having wings h h, to be turned down over said projection upon the glass, substantially as set forth.
5. In a glazed roof, the combination, with the sheets of glass, of a glazing-bar, A, having ledges a, for supporting the edges of the glass, and a projection, C, extending up above the glass, a sealing-strip, D, fixed to said projection, and having wings h h, to be turned down

over said projection upon the glass, and angle-strips k k, inserted over the edges of the glass against said projection, substantially as set forth.

6. In a glazed roof, the combination, with the sheets of glass, of a glazing-bar, A, having ledges a, for supporting the edges of the glass, and a projection, C, extending up above the glass, a sealing-strip, D, fixed to said projection, and having wings h h, to be turned down upon the glass, and a yielding packing placed against the edge of the glass and covered by said turned-down wings, substantially as set forth.

7. In a glazed roof, the combination, with the sheets of glass laid to overlap each other, of a glazing-bar, A, a sealing-strip, D, fixed thereto, and having wings h h, to be turned down upon the edges of the glass, and angle-strips k k, placed over the edges of the sheets, with their upper ends abutting against the overlapping edges of the sheets of glass above and fastened to the bar A, substantially as set forth, whereby the slipping down of the glass is prevented.

8. In a glazed roof, the combination, with the sheets of glass, of the glazing-bar A, having ledges a a, and one or more gutters formed on its sides, the sealing-strip D, fixed to the glazing-bar, and the strip E, having gutters m m, fastened beneath the glazing-bar, substantially as set forth.

In witness whereof I have hereunto signed my name in the presence of two subscribing witnesses.

THOMAS WILLIAM HELLIWELL.
